TELEPHONE STAND

Andrew J. Prince, 47 Stamford Road,
Mercerville, N.J. 08619

Filed Dec. 11, 1967, Ser. No. 9,724

Term of patent 14 years

(Cl. D26—14)

The figure is a perspective view of a telephone stand embodying my new design, the broken lines representing the telephone directory being shown for illustrative purposes only.

All sides of the figure not shown, except the attached cylindrical holder and support therefor, have uninterrupted plane surfaces parallel with their respective opposite surfaces shown.

I claim:

The ornamental design for a telephone stand, substantially as shown and described.
